UNITED STATES PATENT OFFICE.

HENRY BREEDEN, OF VIENNA, VIRGINIA, ASSIGNOR TO ALBERT SIDNEY WHITE, OF NEW ORLEANS, LOUISIANA.

BARREL.

1,096,674.

Specification of Letters Patent. Patented May 12, 1914.

Application filed July 15, 1913. Serial No. 779,197.

To all whom it may concern:

Be it known that I, HENRY BREEDEN, a citizen of the United States, residing at Vienna, in the county of Fairfax and State 5 of Virginia, have invented certain new and useful Improvements in Barrels; and I do hereby declare the following to be a full, clear, and exact description of the invention, such as will enable others skilled in the art 10 to which it appertains to make and use the same.

My invention relates to metallic barrels and consists in the constructions, arrangements and combinations of parts hereinafter 15 described and claimed.

It is an object of my invention to provide a barrel which will be for all purposes leak-proof, and to this end it consists in an improved fastening for the barrel heads which 20 will present no sharp corners to the metal, but which will provide a smooth joint throughout.

Another object of my invention is to provide a barrel which will be of improved 25 strength and which will consist of a minimum number of parts adapted for ready assembly; each of the parts being simple and economical of manufacture.

In describing my invention in detail, reference will be had to the accompanying drawing wherein like symbols refer to like or corresponding parts throughout the several views, and in which:—

Figure 1 is a vertical sectional view of a 35 barrel made in accordance with my invention; Fig. 2 is an enlarged sectional view of a corner of the barrel; Fig. 3 is an elevation of my improved clamping ring partly shown in section; and Fig. 4 is an elevation 40 of my reinforcing ring partly shown in section.

Referring more particularly to the drawings, 1 designates the body portion of a barrel made in accordance with any approved 45 design and method; and 2 designates the barrel heads which are preferably of the dished type, as shown. The peripheral edges of the heads 2 are turned outwardly to provide substantially cylindrical walls, or 50 flanges, 3 adapted to fit snugly within the ends 4 of the body 1. As compared with similar structures in the art, it will be noted that the walls 3 and ends 4 are unusually deep to permit of being bent over, as herein-

after explained. A reinforcing ring 5, flat 55 or band-like in cross section, having rounded edges, as shown, and provided on its outer face with one or more horizontally-running corrugations 6, is fitted within the flange 3 and the metal of the flange is rolled into 60 the corrugations, as advantageously illustrated in Fig. 2. An annular strengthening flange 7 projects inwardly, preferably from the lower edge of the reinforcing ring 5, and has its base shaped to follow the contour of 65 the barrel head 2, so as to lie in contact therewith throughout. The flange 7 is enlarged vertically to provide a shoulder 8 in spaced relation to the inner face of the reinforcing ring 5 against which the 'over- 70 turned ends of the body portion and head flanges are adapted to abut. These ends are preferably welded into the shoulder, whereby a strong and smooth joint is provided.

An outer clamping ring 9 having a corrugated inner face 10 corresponding to the corrugations 6 in the reinforcing ring 5 is mounted over the outer ends 4 of the barrel body, and preferably shrunk in place. A protecting flange 11 extends inwardly from 80 the upper edge of the clamping ring 9, and overlaps the reinforcing ring 5 whereby all the shocks and strains imposed on the joints during transportation and use are received by the clamping ring 9 and its flange. 85

In assembling the parts, the reinforcing ring 5 is preferably inserted in place within the flange 3, and the metal of the flange rolled into the corrugations, after which the head may be fitted in place within the ends 4 90 of the barrel body, whereupon the operation of rolling is continued upon the ends 4. Thereupon the free ends of the head-flange and body above the reinforcing ring 5 are together bent over the latter and rolled into 95 close contact with the inner face thereof, the extremities bringing up against the shoulder 8 where a weld is wrought. The clamping ring, being seamless, is heated to the proper temperature and shrunk in position to bind 100 the metal walls 3 and 4 tightly together.

Shocks and strains incident to usage and imposed upon the clamping ring 9 are transmitted to the reinforcing ring 5 which resists bending assisted by the flange 7, which 105 covers a large area of the barrel head and thereby affords a protection from both interior and exterior forces.

I have shown and described preferred and satisfactory constructions, but desire it to be understood that slight changes may be made without departing from the spirit of the invention, provided such changes fall within the scope of the appended claims.

I claim:-

1. A metallic barrel comprising a body portion, a flanged head inclosing said body portion, a reinforcing ring fitting the flange on said head, a shouldered flange projecting from said reinforcing ring, the ends of said head-flange and body portion being bent over said reinforcing ring and bringing up against said shoulder to provide a smooth joint, and a clamping ring mounted over the end of said body portion substantially concentric with said reinforcing ring.
2. A metallic barrel comprising a body portion, a flanged head inclosing said body portion, a corrugated ring fitting the flange on said head, a shouldered flange projecting from said reinforcing ring, the ends of said head-flange and body portion being bent over said reinforcing ring and bringing up against the shoulder, a weld wrought between the ends of said head-flange and body portion and said shoulder, and a corrugated clamping ring mounted over the end of said

body portion substantially concentric with 30 said reinforcing ring.

3. A metallic barrel comprising a body portion, a flanged head inclosing said body portion, a reinforcing ring fitting the flange on said head and having its outer face corrugated, the metal of the flange and adjacent body portion being rolled into the corrugations, an annular shouldered flange projecting inwardly from said reinforcing ring, the ends of said head-flange and body portion being turned over said reinforcing ring and bringing up against the shoulder, a weld wrought between the ends of said head-flange and body portion and the shoulder, a clamping ring having its inner face provided with corrugations to correspond to the corrugations on said reinforcing ring and mounted over the end of said barrel, and a flange projecting inwardly from said clamping ring and overlapping the outer edge of 50 said reinforcing ring.

In testimony whereof, I affix my signature, in presence of two witnesses.

HENRY BREEDEN.
